UNITED STATES PATENT OFFICE.

FRANK G. HOGLAND, OF CHICAGO, ILLINOIS, ASSIGNOR TO ILLINOIS SEWING MACHINE COMPANY, OF CHICAGO, ILLINOIS, A CORPORATION OF ILLINOIS.

DESIGN FOR A SEWING-MACHINE TABLE.

SPECIFICATION forming part of Design No. 36,004, dated August 12, 1902.

Application filed July 10, 1902. Serial No. 115,101. Term of patent 7 years.

To all whom it may concern:

Be it known that I, FRANK G. HOGLAND, a citizen of the United States of America, residing at Chicago, in the county of Cook and State of Illinois, have invented and produced a new, original, and ornamental Design for Sewing-Machine Tables; and I do hereby declare the following to be a full, clear, and exact description of the same, reference being had to the accompanying drawings, forming a part thereof.

In the drawings, Figure 1 is a perspective view, and Fig. 2 a rear elevation, of my new design for sewing-machine tables.

The sewing-machine table comprises the top A, having its front edge and end portions formed in curves, as shown, the frame B, having its front edge curved to coincide substantially with the front edge of the top A, cover C, having its front edge curved to coincide substantially with the front edge of the frame B, horizontal drawer-supports D, drawers E,

having their ends and outer sides curved to coincide substantially with the corresponding end portions of the top A, vertical door-posts F, ogee-curved in transverse section, swell-front doors G, having their lower ends cut away to form therein the upward curves H, which are bordered and adorned with the carved ornamentation I and the strips of the astragal J, ornamenting the straight portions of the lower ends of such doors.

Having described my invention, what I claim as new, and desire to secure by Letters Patent, is—

The ornamental design for a sewing-machine table herein shown and described.

In testimony whereof I have signed my name to this specification in the presence of two subscribing witnesses.

FRANK G. HOGLAND.
